SAND CLASSIFYING AND DEWATERING APPARATUS

Walter E. Saxe, Pasadena, Calif., assignor to The Conveyor Company, Inc., Los Angeles, Calif., a corporation of California

Application December 23, 1948, Serial No. 67,004

6 Claims. (Cl. 210—196)

1

This invention relates to mechanical structures for the removal of excess liquid from various liquid-containing masses commonly known as pulps which comprise the liquid and varying proportions of solids. More especially, the invention relates to apparatus for separating the water content from granular materials such as wet sand and similar siliceous or mineral bearing pulps.

One object of the invention is to provide an efficient apparatus capable of speedily reducing the water content of large volumes of wet, solid materials to very low proportions, for example, to as low as about 5% from water contents as high as about 80%. Thus, it is desirable to reduce the water content of sand loaded at large sand plants to such a minimum that water will not drip from trucks or railway cars during transportation, and at the same time haulage and freight costs otherwise payable on such excess water are saved. Similarly, in such operations as cyaniding gold sands by leaching, speedy recovery of enriched leaching solutions without waiting for percolation through the sands is economically desirable, as is good pre-drying before fire drying of sands for glass manufacture and the like.

It is also an object of the invention to provide in the same apparatus means for reducing the water content of sands while providing also for classification of the sands before de-watering and without the necessity of employing separate classifying apparatus ahead of the de-watering means. An incidental object is to provide in such a classifying device means for relying upon a variable rising liquid column or a variable stream length, or a variable area of the rising column as a classification agent.

An additional object is to provide efficient de-watering means having high liquid flow capacity, ability to remain open and function without clogging, and ability to retain the fines desired so that little or none of the desired product is lost or returned to the circuit.

Still another object of the invention is to provide a device in which suction is relied upon for the purpose of removal of the desired proportion of liquid from the solid material, and air or other gas under pressure is relied upon to insure positive discharge of the so dried solid

2

product, it being a still further object to provide means for applying liquid to those portions of the apparatus from which the dried material has been discharged whereby to condition them for further reception of pulp to be treated.

A further object is to provide a de-watering structure in which bristles in a substantially flat brush formation may be employed to accomplish the desired rapid liquid flow without loss of fines or clogging, or in which bristles are employed in the bottoms or sides of buckets or other containers as filtering or separating agents through which excess water passes.

Other objects and advantages of this invention, together with the various features thereof, will become apparent to those skilled in this art upon reference to the following specification and the accompanying drawings wherein certain embodiments of the invention are illustrated for the purpose of exemplification. While reference is generally made in the descriptive matter to a water and sand pulp, it is to be understood that the invention is useful also in connection with other appropriate liquid carrying solids.

In the drawings:

Fig. 1 is an elevational view of one end of apparatus embodying the improvements hereof, this view being taken from the right side of Fig. 2 as indicated by the arrow;

Fig. 2 is a vertical longitudinal section taken approximately from the line 2—2 of Fig. 1;

Fig. 3 is a vertical cross section taken approximately on the line 3—3 of Fig. 2;

Fig. 4 is an enlarged sectional detail of one of the bucket conveyors and associated mechanism seen in Fig. 3;

Fig. 5 is a sectional view taken approximately on the line 5—5 of Fig. 4;

Fig. 6 is a considerably enlarged fragmentary detail showing the relationship of water-pervious supporting means for granular materials being separated from the pulp;

Fig. 7 is a sectional detail similar to that of Fig. 4 and showing a somewhat modified form of bucket structure, as indicated by the line 7—7 of Fig. 8;

Fig. 8 is a section taken approximately on the line 8—8 of Fig. 7;

Fig. 8A is a sectional detail showing a slight modification of the bucket of Figs. 7 and 8;

Fig. 9 is an elevational view similar to that of Fig. 1 and shows a modified form of apparatus; and

Fig. 10 is a plan view of the apparatus of Fig. 9. As illustrated, especially in Figs. 1, 2 and 3, the apparatus comprises a wheel or rotary bucket type of conveyor generally indicated at C which is mounted to rotate between opposite portions of a framework generally indicated at F, the lower portion of the bucket conveyor dipping into a sand or similar pulp P contained within a rectangular pulp-receiving tank T which acts as a classifier and is open at its top. The periphery of the conveyor C is provided with a plurality of buckets generally indicated at B adapted to pick up a predominant proportion of solids which settle in the tank T. A modified form of bucket B2, as shown at the top of Fig. 3 and in Figs. 7 and 9, also, may be used.

The framework F comprises a plurality of standards 10 and a plurality of standards 11, the standards 10 carrying appropriate supporting cross bars 12 and the standards 11 carrying various platforms 13 and 14. One of the bars 12 at an intermediate portion of the framework F on each side of the conveyor C carries the respective end of a shaft 15 of the conveyor C, appropriate bearings 16 serving to journal the ends of this shaft as seen in Fig. 1. The middle portion of the shaft 15 has affixed thereon a pair of spaced hubs 17 which support and drive spaced, disc-like plates 18 of the conveyor C, the outermost portions of the plates 18 being joined in the form shown to frusto-conical connection walls 19, the outermost portions of the walls 19 being in turn secured to annular end plates 20 which constitute peripheral portions of the conveyor C.

For the purpose of driving the rotary conveyor C, the platform 13, which is located at one end of the structure as indicated in Figs. 1 and 2, carries a motor 22 which drives a chain 23 passing over a sprocket 24 mounted upon a drive shaft 25 having a pinion 26 meshing with a gear 28 secured upon one end of the conveyor shaft 15. Mounted at one side of the apparatus upon the platforms 14, which are located adjacent both ends of the apparatus, are air pumps 30 which are driven by motors 31 through the medium of belts 32 and pulleys 33, each pump supplying a high pressure air line 34 at its discharge side, and receiving through a suction line 35 and a T 35a at its intake or low pressure side, for the purpose of successively subjecting the buckets B to suction and high pressure effects as later to be described. The line 35 and T 35a have adequate capacity for handling a suction air stream in addition to water being withdrawn from the buckets B. At the side of the apparatus opposite the pumps 30 high pressure water supply pipes 36 (Fig. 1) are positioned for the purpose of supplying water under pressure to each end of the conveyor C and to the buckets B, as also presently to be described. Such high pressure water may be furnished by any means not shown.

The buckets B of the rotary conveyor C are provided in two circular series as illustrated in Fig. 2, the adjacent buckets B of the two series being arranged end-to-end in pairs and separated by partitions 40. The opposite or outer ends of the buckets B may be formed by corresponding portions of the annular end plates 20, as in Fig. 5, or may be separate end walls 40a as in the forms of Figs. 8A, 9 and 10. One construction for each of the buckets B, which is best detailed in Fig. 4, includes a generally flat, out-

wardly disposed side wall 41 which is angularly positioned with respect to the corresponding radius, the upper extension 41a of the side wall 41 being roughly perpendicular to the corresponding radius. Opposed to the side wall 41 of each bucket is a generally flat, inwardly disposed side wall 42 arranged approximately perpendicular to the corresponding radius. One end of this wall 42, which may for convenience be termed the lower end, is rolled to provide a curved portion 42a which is welded to the adjacent portion of the wall 41 and may be termed a curved bottom portion. The side walls 41 and 42 in general provide the bottoms of the respective buckets B when the buckets serve as containers, the actual effective bottom portions varying as the buckets change their positions during rotation of the conveyor C in the direction of the arrows shown in Figs. 1 and 3.

The curved bottom portion 42a of each wall 42 slopes laterally outward from the respective partition 40 to the respective end plate 20, so that the lowermost end of the curved portion 42a communicates with and drains to a corresponding opening 44 in the respective end plate 20, such opening 44 constituting a passage for air and liquid. Thus, each end plate 20 is provided with an opening 44 for each of the buckets B, these openings 44 being adapted to communicate successively with suction and pressure manifolds and alternately with the atmosphere. The advancing portion of each bucket B, which is opposite from the curved bottom portion 42a and therefore may be considered the top of the bucket, is necessarily open both for the reception of pulp and for the discharge of de-watered solids. As also seen in Fig. 4, the edge of the wall 42 opposite from the curved bottom portion 42a is sealed against the lowermost edge portion of the outer wall 41 of the immediately preceding bucket B. This sealed joint may be effected by welding, as may the other joints between the various parts of the buckets.

At an intermediate position in each of the buckets B there is disposed a supporting wall 45 for solids being de-watered. This wall 45 is removably mounted in its respective bucket, and this is accomplished by welding an angle bar 46 to the inner face of the outer side wall 41 of the respective bucket and another angle bar 47 to the wall 41 of the adjacent bucket. The edges of the supporting wall 45 are flanged to engage the angle bars 46 and 47 and are secured in place by means of short bolts 48 which are threaded into nuts 49 welded in place on the under sides of the respective angle bars. Thus, the bolts 48 may be easily removed with socket wrenches in order that the respective supporting wall 45 may be replaced. The ends of each wall 45 are sealed against its partition 40 and the adjacent portion of the respective end plate 20 by any appropriate means. Each supporting wall 45 is provided with a series of rectangular apertures 50 in which are positioned various groups or tufts of bristles 51 of common rectangular brushes having rectangular backs 52. The tips of the bristles 51 of each brush provide a flat filter surface and are confined against spreading laterally by the edges of the wall 45 of the respective aperture 50. The bristles 51 are positioned in their apertures 50 and the respective brushes are held to maintain such position by wood screws 53 which are screwed into the brush backs 52 and are received in positioning straps 54 whose ends are

offset and riveted or otherwise appropriately secured to the respective supporting wall 45 as indicated at 56, or are secured by the bolts 48. The base of each tuft of bristles 51 is compacted by drawing the bristles together and securing the tuft base in the respective brush back 52 in a conventional manner. When suction is applied through the respective opening 44 to the chamber 58 enclosed by the various walls 41, 42 and 45, whereby to draw water through the bristles 51, the latter serve as a very effective barrier and filter medium which prevents the sand or other granular material or similar solids from passing through the lower portions of the tufts with the water. Also, the bristles 51 rather readily release granular particles by a subsequent blowing operation wherein air under pressure is passed in a reverse direction through the bristles 51, as well as by a subsequent washing operation where water under pressure is similarly passed through the bristles in such reverse direction.

As the bucket conveyor C advances to move the respective openings 44 of the various buckets B in the direction indicated by the arrows shown in Figs. 1 and 3, some of the excess water may first drain out through the bristles 51. This continues until any given opening 44 comes into communication with a channel 60 in a suction manifold 61 which contacts the respective end plate 20 and is connected to the suction line 35 and T 35a leading to the intake side of the respective pump 30. Thus, suction effects are produced in each of the buckets B as long as its opening 44 communicates with the suction manifold 61, suction continuing until the bucket has passed slightly beyond top center as viewed in Figs. 1 and 3. The respective opening 44 is then exposed to the atmosphere for a short interval, following which it comes into communication with an air channel 62 in a pressure manifold 63 supplied with air under pressure from the high pressure line 34 by way of a line 34a. This air pressure assists in loosening the sand or other de-watered solids so that the solids are discharged to a chute 65 or the like illustrated in Fig. 3. During this discharging stage the outer surfaces of the various outer side walls 41 serve as means to direct the solids being discharged to the chute 65. The air under pressure also serves at this time to clear out most of the sand from the bristles 51.

Any given bucket B having been emptied of its de-watered solids, its opening 44 passes from the air manifold 63 and, following an interval of communication with the atmosphere, arrives at a high pressure water manifold 66 (Fig. 1) having a channel 67 which communicates with the corresponding water supply pipe 36. The high pressure water entering through the respective opening 44 fills the respective chamber 58 and then passes through the bristles 51 of the brushes whereby to dislodge and wash out any solid material remaining in the bristles. This wash water, together with accompanying solids, is discharged into the tank T at the left side of the apparatus as viewed in Fig. 3. If desired, each water manifold 66 may extend down into the pulp P in the tank T so that a portion of the washing may take place after submergence of the respective bucket B.

In order to maintain an adequate sealing between each of the manifolds 61, 63 and 66, with the annular end plates 20 of the conveyor C, appropriate packing means 70 (Fig. 2) is secured

to flanged portions of the manifolds in any manner appropriate for sliding engagement with the end plates 20. Such packing material may be in the form of rubber layers vulcanized or otherwise suitably secured, such rubber being natural or synthetic, as most desirable or other acceptable packing materials and arrangements may be used. To insure adequate contact of the manifolds 61, 63 and 66 and their packing material 70 with the plates 20, assisting means may be provided, such as spring controlled pressing devices 72 illustrated in Fig. 2, these devices being carried in appropriate sockets 73 or other holders mounted upon the upper cross bars 12 at the tops 15 of the standards 10. Bracket means 74 (Fig. 2) may be employed for proper positioning of the various manifolds. In the case of the manifolds 66, means such as brackets 75 (Fig. 1) carried by adjacent portions of the tank T may serve to 20 carry suitable assisting means corresponding with the devices 72.

The high pressure water introduced through the manifolds 66 is returned to the tank T for the purpose of recovering solids removed therefrom by the bristles 51. The water withdrawn through the suction manifolds 61 is received by traps 76 (Figs. 1 and 2) into which the water is delivered by drainage pipes 76a which connect with the high pressure lines 34 and T's 35a positioned at the bases of the suction manifolds 61. The water may be returned from each trap 76 to the tank T, as by a line 77 and a pump 78 (Fig. 1), to provide a suitable water flow for classification purposes, or as described below in connection with the form of Figs. 9 and 10. Again, the water may be discharged to waste as through a line 79. Any appropriate liquid head may be established to offset the pull of the vacuum pumps 30.

Pulp to be de-watered is supplied to the tank T at any appropriate point such as the inlet indicated at 80 (Fig. 3), and a baffle 81 is preferably employed to direct the solids downward and to some extent segregate the feed from the moving buckets B. The water level is maintained at any satisfactory height to obtain desired classification of the pulp in the tank T. This may be established by overflow launders or troughs 82 (Fig. 2) through which leaves, small sticks, and other waste and fines may be discharged from the system in the excess water. The troughs 82 are carried upon appropriate brackets 82a within the tank T and are provided with vertically adjustable upper edge strip members 83 which are mounted as by bolts and slots 83a to vary the overflow level or the effective length of the trough edges passing overflow water and, hence, to vary the relative agitation or quiescence in the tank T as the nature of the feed requires. Such overflow water is discharged from the system by means of drainage pipes 84 leading from the bottoms of the troughs 82 and passing outward through the sides of the tank T. Thus, as heavily watered pulp is fed into the tank T and the solids settle in the bottom of the tank, the accumulating, supernatant water and light materials separated from the desired solids escape. If necessary, the strip members 83 may be angularly adjusted to serve as levelling means for the tank troughs 82, if the apparatus is not level, or they may be angularly or vertically adjusted to vary the proportion of the trough edges over which water may flow by raising corresponding portions of the members 83 to positions above the pulp level, thereby also varying the effective top

area of the effective rising column and further vary the agitation, settling and classification, as well as varying the effective stream length of the moving pulp within the tank T. All of these factors may be relied upon to regulate classification.

As the bucket conveyor C rotates in the indicated direction, the various buckets B (B2) scoop up settled solids from the bottom of the tank T together with a relatively large amount of liquid, such solids being caught in the buckets as their mouths approach the top of the tank T. Water which separates and passes through the bristles 51 by gravity as the buckets are lifted above the liquid is drained back into the tank T by way of the openings 44, until such time as the respective openings 44 pass to the channels 60 in the suction manifolds 61, whereupon the suction effects draw the liquid, freed from solids, through the bristles 51, such liquid draining into the traps 76 as above indicated. The liquid having been removed by the preliminary gravity drainage and by the succeeding suction operation, the openings 44 leave the manifolds 61 and, after a brief communication with the atmosphere, pass to the manifolds 63. At approximately this position the de-watered solids tend to fall from the respective buckets B, and this is assisted by the air streams passed through the bristles 51 under influence of the high pressure air supplied by the high pressure line 34 and the connecting line 34a. A very small proportion of de-watered solids tends to stick in the bristles 51 after the dumping and blowing operations and this is flushed out next by high pressure water received through the water manifolds 66.

When desired to increase gravity separation of excess water picked up in the buckets, a modified form of bucket B2 (illustrated at the top of Fig. 3 and in Figs. 7 and 8, and similarly in Fig. 9) may be employed. Here substantially the same side walls 41 and 42 are employed as in the other form, and substantially the same supporting wall 45 located above the suction chamber 58 is employed for each bucket B2. In this instance the walls 43 and 41 may be secured to the end plates 20 by means of rivets 85 and flanges 86. However, in this form the side wall 42 has an extension 87 whose upper edge portion is bolted to the lower edge of the side wall 41 of the preceding bucket B2, and whose intermediate portion is provided with a series of relatively large openings 88 filled with banks of louvers 90 which are sufficiently closely positioned to retain solids being handled. These louvers may be integrally formed by striking up from suitable metal plates 91 whose edges are bound into position by screws or bolts 92, or the louvers 90 may be formed in any other appropriate manner. Thus, the spaces between the louvers 90 are disposed to discharge supernatant water back to the tank T through the interior of the wheel or rotary conveyor C, this return being necessary inasmuch as such drainage water will necessarily contain some solids which need to be recovered. Such water reaches the tank T through the louvers 90 and the sand-receiving portions of those buckets which are then submerged in the tank T. By employment of the banks of louvers 90, a large proportion of the excess water picked up from the pulp bed in the tank T by the rising buckets as the conveyor C rotates flows out through the louvers and correspondingly reduces the load required of the suction system. Also, as the body of solids tends

to fall forward during rotation of each bucket, de-watering will be further facilitated by drainage through the louvers 90. The operation of this modification of the buckets B is similar to that of the other form, but a larger proportion of the excess water is separated by gravity drainage. This indicated return of water from the buckets B and B2 insures an adequately large water supply to classify and wash the solids, as required, before they pass into the buckets, and adjustment of the edge members 83 regulates the classification.

In the form of apparatus shown in Figs. 9 and 10, the buckets B2 are of substantially the same construction as those of Figs. 7 and 8, as presently to be described, but the construction of the bucket conveyor, generally indicated at C2, is somewhat different from that of the bucket conveyor C of Figs. 1 to 3, and the means for handling the returning water is different.

In Figs. 9 and 10, a tank T2, which is of rectangular design and open at its top corresponds with the tank T of the other form and has the rotary bucket conveyor C2 arranged so that the buckets B2 dip into the water bearing pulp as in the other form of construction. A framework F2, of somewhat simpler construction than the framework F of the other form, is shown as comprising standards 110 at opposite sides of the tank T2 to support the conveyor C2, and the standard 111 disposed adjacent the standard 110 on the driving side of the apparatus, the standard 111 being connected with an intermediate portion of the standard 110 by means of a crossbar 112.

The conveyor C2 is actuated and supported through the medium of a shaft 115 whose opposite ends rest in appropriate mountings 116 mounted upon the tops of the standards 110. Adjacent the mountings 116, the shaft 115 is provided with a pair of spaced hubs 117 (Fig. 10) provided in disc-like plates 118 which constitute the ends of a driven drum 119 which is indirectly connected to annular end plates 120 and an intervening partitioning plate 120a, also of annular formation. The end plates 120 and the partitioning plate 120a together with the buckets B2 and the driven drum 119 constitute the principal portions of the conveyor C2. In the form shown, the inner edges of the plates 120 and 120a are affixed to a driven drum 121 which is concentric with the driven drum 119, and the two drums 119 and 121 are rigidly connected in driving relation by means of interposed annular rings 122 welded in position, as shown, so that the conveyor C2 as a unit may be driven through the medium of the drum 119. In order to effect such driving of the drum 119, a sprocket 124, adapted to be driven by an appropriate chain from any prime mover (not shown) is provided upon a sub-shaft 125 mounted in a bearing 125a on the top of the previously mentioned standard 111. The inner end of the sub-shaft 125 has fixed thereon a pinion 126 which meshes with a large gear 128 which is appropriately fixed to the adjacent end of the driven drum 119 projecting beyond the tank T2. By these means the bucket conveyor C2 is rotated upon the supporting shaft 115, on the mountings 116 as above indicated.

The buckets B2, which are substantially the buckets of Figs. 7, 8 and 8A, have the same louvers 90 formed in the same metal plates 91 provided in the same extensions as the same side walls

42 of the buckets and with substantially the same outward side walls 41, 41a, whose outer surfaces serve to guide the de-watered solids of the respectively succeeding buckets as the solids are discharged following rotation beyond top center of the conveyor. As indicated, the ends of the buckets B2 may have the separate end walls 40a seen in Fig. 10, and corresponding generally with the end walls 40a of Fig. 8A, or their end walls may be provided by the end plates 120 and the partitioning plate 120a in general conformity with the construction shown in Figs. 5 and 8 where the end plates 120 and the partition 40 are employed as ends of the buckets B. Also, substantially the same intermediate supporting walls 45 are employed to carry the same rectangular brushes composed of tufts of bristles 51 and brush backs 52 as in the other form and as illustrated in greater detail in Figs. 4 to 7, inclusive. However, the rearward or bottom portion of each of the inward walls 42 is directed more distinctly radially outward than is the curved bottom portion 42a of the form of either Fig. 4 or Fig. 7, such radially directed portions being indicated at 42b in Fig. 9.

Since the mechanism for producing suction in the buckets B2 of the conveyor C2 of Figs. 9 and 10 is located at the central or hub portion of the rotary conveyor C2, the means for producing partial vacuum effect in the chambers 58 of the respective buckets are made in the form of conduits 135 which are directed substantially radially inward as best seen in Fig. 9 and are connected with the chambers 58 adjacent their outer ends as best seen in Fig. 10. The inner ends of the conduits 135, which correspond in a general way with the outlets 44 from the chambers 58 of the structure in Figs. 1 to 5, are rigidly connected to the outer driven drum 121 at positions outside of the end annular driving rings 122 (Fig. 10). These connections are made by appropriately fitting the ends of the conduits 135 in openings 136 provided in the respective end portions of the drum 121. The ends of the conduits 135 are thus adapted, as the conveyor C2 rotates in the direction of the arrows seen in Fig. 9, to communicate with at least one of a series of peripheral openings 138 provided in an annular valve 140 which is non-rotatably mounted upon each end portion of the inner driven drum 119. The series of openings 138 in each annular valve 140 extends through that portion of the periphery of the respective valve member 140 which corresponds with that portion of the path of travel of each bucket B2 during which the suction chamber 58 of the respective bucket B2 is to be placed under partial vacuum. This range extends from approximately the horizontal as seen at the right of Fig. 9 to a position somewhat beyond top center as is illustrated at the upper left of Fig. 9. The rest of the peripheral portion of each valve 140 is imperforate so that suction is cut off as any given bucket B2 moves over to discharging position and is not restored until the bucket has passed through the tank, picked up its load of sand, and risen to a position above the water level in the tank, or approximately to a horizontal position. In order to seal the connections between the annular valves 140 and the conduits 135, appropriate annular sealing means 142 is employed between each annular valve 140 and the respective end of the outer driven drum 121. Each valve 140, which acts as a manifold, is hollow as seen in the top of Fig. 10 and extends

outward along the inner driven drum 119 to a position where its upper portion is connected with one end of an upper suction conduit 145 through which air moves, and for connection of its lower portion with a lower suction conduit 146 through which water sucked through the brushes 51, 52 is removed.

The conduits 145 and 146 extend rearward along the ends of the bucket conveyor C2 to a receiving chamber 148 which is placed under partial vacuum by an appropriate vacuum pump 150 which may be mounted on the top thereof. The valves 140, being rigidly connected to the forward ends of the conduits 145 and 146, are held against rotation, inasmuch as the opposite ends of the conduits 145 and 146 are held against movement by reason of their attachment to the chamber 148. Water returning through the lower conduit 146 falls into the bottom of the chamber 148 where it is appropriately removed. Preferably the water is picked up by a centrifugal pump 152 (Fig. 9) driven by a motor 153 or the like on top of the chamber 148 and forced through lines 154 along the opposite sides of the tank T2 to discharge points near the forward ends thereof and below the normal water level. In this manner, adequate water is continuously supplied to the tank T2 to provide ample water supply for any required classification of the feed material, such as sand, before the desired solids are picked up by the buckets B2.

When the classified sand is picked up in a bucket B2 settling promptly occurs, and the supernatant water proceeds to flow out through the louvers 90 as soon as the bucket moves above the water level. At this stage, the inner ends of the conduits 135 within the rotary conveyor C2 come into communication with the valve openings 138 in the adjacent portions of the stationary annular valves 140. Also, at this stage, the partial vacuum created in the system by the vacuum pump 150 begins to draw remaining water through the bristles 51 on the brush backs 52, the water passing into the hollow valves 140 and falling into the receiving chamber 148. As long as any supernatant water remains it continues to flow through the louvers 90, and residual water continues to be removed by the effect of the partial vacuum in the system until the respective suction conduit 135 has passed beyond the last valve opening 138 in the direction of travel of the conveyor C2. At this stage, the de-watered sand begins to fall from the respective bucket B2, slide down over the adjacent outer wall 41 of the preceding bucket, and is discharged from the apparatus over a chute 165 corresponding generally with the chute 65 of Figs. 1 and 3.

As best indicated in Fig. 10, the feed materials are introduced into this form of apparatus at the forward end of the tank T2 adjacent both corners thereof near the ends of the chute 165. These feed points are indicated at 180. As in the case of the form of Figs. 1 to 3, the water level is determined by overflow troughs 182 extending longitudinally of the tank T2 at opposite sides thereof beyond the ends of the conveyor C2 at elevations somewhat above the points of discharge of the returning filtrate through the return lines 154. These overflow troughs 182 extend substantially the entire length of the tank T2 so that they may adequately remove surface water and adequately effect desired classification of the feed material. In order to vary the settling rate and thereby vary classification as required, the sides 70 of the troughs 182 are provided with vertically ad-

justable edge strips 183 corresponding with the adjustable edge strip members 83 of the other form. Thus, as the edge strips 183 are raised or lowered through the medium of any adjustment means such as bolts and slots 184, lesser or greater amounts of fines and other light materials are caused to overflow into the troughs 182 and thereby regulate the character of heavy material moving to the middle of the tank and picked up by the buckets B2. The troughs 182 discharge into a receptacle 185 which may in turn be discharged through an outlet 186.

In all forms, raising and lowering of the edge strips 83, 183 vary the pulp head in the tanks T, T2 and correspondingly affect the settling rate of the solids, as will be apparent to those skilled in the art. Again, raising of portions only of the edge strips 83, 183 may be relied upon to decrease the overflow length along the tops of the troughs 82, 182, and thus decrease the effective area of the rising liquid columns and affect the settling rate and classification accordingly. This will be further affected by the consequent lengthening or shortening of the path through which the liquid must pass to the overflow points.

It will be evident from the foregoing that the classification of the feed material, and the removal of water from the sand picked up by the buckets B2, are substantially the same as in the other form of the invention. As previously described in connection with the bucket structure B2 of the form of Fig. 7, the supernatant water flowing out through the louvers 90 falls within the rotary conveyor C2, and thereby returns to the tank and to the buckets any sand which may have escaped through the louvers 90. Such falling water and sand returns to the buckets through the louvers 90 in the same way in which they escape therefrom.

In all instances, the substantially flat filter surfaces presented by the tips of the bristles 51 of the various brushes serve perfectly to retain all sand, possibly aside from very fine materials which escape classification, and to permit the passage of water under the influence of the suction of the system without clogging of the brushes. This filtering means, wherein the tips of the bristles are confined by the edges of the respective openings 50, surpasses in effectiveness all other filtering agencies, both from the standpoint of speed and thoroughness. In addition, the present apparatus, by reason of the described classification features and characteristics, eliminates the necessity for the employment of a separate classifying agency before passage of the feed material to the tank supplying the buckets.

The return of the water by the pumps of both forms of the invention into the classifying tanks T and T2 below the pulp assists rather than retards classification, and the return through the wheel conveyor of water escaping from the buckets through the louvers 90 avoids disturbance of the classification zones by the falling water, while the passage of such returning water back through the louvers aids in rejecting unwanted fines at the pickup point of the buckets. Again, any desired sand returned to the vacuum chamber 148 and thence to the tank by the lines 154 is thereby recovered.

In operating the rotary de-watering structure of either form of this invention, I have found it possible to reduce the water content of a pulp containing about 80% water to a water content of only about 5% with a vacuum in the order of 6 inches to 7 inches of mercury. In employing

an apparatus where the rotary bucket conveyor has a diameter of fourteen feet and eighteen buckets are provided in each circular series, a capacity of 250 tons per hour has been reached.

Since variations of the specific forms disclosed will become apparent to those skilled in this art, it is intended to cover all such modifications as fall within the scope of the patent claims.

I claim as my invention:

1. In combination in a classifying and de-watering apparatus: a classifier tank adapted to receive a water pulp containing solids to be classified and de-watered; a rotary conveyor; and buckets arranged on said conveyor about its periphery for dipping into said tank to pick up pulp in said tank, said buckets having water-pervious wall portions capable of supporting solids while passing water therethrough, said conveyor comprising substantially solid end walls between which said buckets are mounted, said end walls and buckets substantially enclosing the interior of said rotary conveyor, at least certain of said water-pervious wall portions discharging into said enclosed interior of said conveyor, whereby water discharged thereby does not fall into the portions of pulp being classified in said tank, said end walls having outlets, and water discharging means communicating with said outlets to remove water therethrough.
2. A combination as in claim 1 wherein said certain of said wall portions are disposed to serve as side walls of said buckets as the latter rise, whereby supernatant water flows therethrough, and wherein other water-pervious wall portions constitute bottom portions as said buckets rise and include filter members for passage therethrough of drainage water from solids supported thereon.
3. A combination as in claim 2 including differential air pressure means connected with said filter members for passage of drainage water therethrough, and means for conducting such drainage water beyond the surface of the pulp undergoing classification in said tank.
4. In combination in a device of the class described: a classifier tank having flow control means to provide desired classification; a rotary wheel-type conveyor dipping into said tank and having end walls; a plurality of buckets fixedly mounted at the periphery of said conveyor between said end walls, said buckets having water-pervious walls; means providing chambers for reception of water passing through certain of said pervious walls; duct means connected with said chambers to place the latter under differential air pressure, said duct means extending radially inward toward the axis of said conveyor; valve manifold means about the axis of said conveyor for communication with said duct; means for conducting water from said manifold means; a receiving chamber connected with said water-conducting means; and means for returning water from said chamber to said tank to provide necessary classification volume.
5. A combination as in claim 4 wherein certain of said water-pervious walls provide for discharge of supernatant water from upper buckets to the interior of the conveyor between its ends whence such discharged water may fall upon inner walls of lower buckets.
6. A combination as in claim 4 wherein said end walls of said conveyor have ports communicating with said chambers, and the said duct means have sealing, sliding contact with said end walls for communication between said ducts and

13

chambers to impart suction and pressure applications to said chambers.
